UNITED STATES PATENT OFFICE.

DUNCAN R. CLARK, OF FOREST CITY, IOWA.

MOUTHPIECE FOR CLARINETS AND SAXOPHONES.

1,411,563.

Specification of Letters Patent. Patented Apr. 4, 1922.

Application filed December 8, 1919. Serial No. 343,170.

To all whom it may concern:

Be it known that I, DUNCAN R. CLARK, a citizen of the United States, residing at Forest City, in the county of Winnebago and 5 State of Iowa, have invented certain new and useful Improvements in Mouthpieces for Clarinets and Saxophones, of which the following is a specification.

This invention relates to mouthpieces for 10 musical instruments, such as clarinets and saxophones, and the primary object of the invention is to provide an improved mouth piece, in which the vibration of the upper wall thereof is reduced, and in which the 15 vibration is prevented from being transmitted to the teeth of the musician playing the instrument.

Another object of the invention is to provide a mouth piece for musical instruments 20 having an inlay of soft shock absorbing material, so that the vibration of the reed will not be transmitted to the teeth of the user and to permit of a better grip being obtained on the mouth piece, so as to facilitate the playing thereof.

A further object of the invention is to provide an improved mouth piece having a thickened upper wall, which will reduce the vibration thereof and permit a larger opening 30 to be made of the front part of the mouthpiece where the tones first enter the instrument, thereby making the tones more mellow and flute like and preventing the choking or pinching of the same.

35 A still further object of the invention is to provide an improved mouth piece for musical instruments of the above character which is durable and efficient in use, one that is simple and easy to manufacture, and one 40 which can be placed upon the market at a reasonable cost.

Other objects of the invention will appear in the following detailed description, taken in connection with the drawings, and in 45 which drawings:

Figure 1 is a perspective view of the improved mouthpiece, showing the inlay in the upper wall thereof.

Figure 2 is a central longitudinal section 50 through the same, and

Figure 3 is a transverse section taken on the line 3—3 of Figure 2.

Referring to the drawings in detail, wherein similar reference characters designate corresponding parts throughout the several 55 views, the letter A indicates the improved

mouth piece having the shock absorbing pad B.

The mouth piece A includes the usual tubular body 5 having the reduced shank 6 60 provided with the friction pad 7.

The upper wall 8 of the body is formed relatively thick, so as to prevent vibration of the same, when the mouth piece is in use. This wall 8 is formed preferably twice as 65 thick as in the ordinary mouth piece, so that the shock absorbing pad B may be placed therein and arranged flush with the outer surface of the wall 8.

The shock absorbing pad B includes a flat 70 body formed of the rubber, cork or other flexible shock absorbing material and has the outer edges thereof bevelled as at 14. The outer surface of the upper wall 8 is recessed as at 15. The end walls of the recess 15 are undercut as at 16 for the reception of the bevelled ends of the pad. In placing the pad in position, the same is slightly bent or compressed so as to force the bevelled ends thereof in the undercut 75 walls 16 of the recess 15. If so desired, the walls however may be formed smooth and the insert glued into position.

The relatively thick wall 8 not only forms means for permitting a seat to be made for 80 the pad, but also allows the inner upper wall to be cut away and hollowed at the very front part of the mouthpiece as at 17, which makes a much larger opening at the point where the tones first enter into the instrument, thus 85 making all tones more mellow and flute like, and eliminates the pinching or choking of the tones. The thickened top wall also makes the mouthpiece more of an even thickness throughout, which causes all tones to 90 resound more evenly, eliminating the vibration so disagreeable and plainly felt by the upper front teeth of clarinet and saxophone players. This thickness of the mouthpiece allows all tones to be produced without inserting the mouth piece so far into the mouth and bringing the point of the reed nearer the tip of the tongue which makes all tongued and staccato notes more clear and distinct, and permits the body of the instrument to 95 be played closer to the body of the player which throws the point of the reed up further which allows a still freer use of the tongue and makes possible double and triple tonguing, as distinct and as clear as on the cornet.

Further the pad B absolutely prevents the

transmission of any vibrations from the front teeth of the user, and permits a firm grip being obtained on the mouth piece and thus prevents slipping of the mouth piece in the 5 mouth of the user.

From the foregoing description it can be seen that an improved mouth piece has been provided, of exceptionally simple and durable construction which will permit the 10 better playing of the instrument and prevent vibration from being transferred to the teeth of the user.

Reed trouble is largely eliminated due to the enlargement of the extreme front or inner 15 upper wall. A much softer reed can be used to obtain the extreme upper tones, which eliminates the hard biting of the upper lip and the harsh tones caused by a stiff reed.

Changes in details may be made without

departing from the spirit of my invention; 20 but,

I claim:

1. A mouth piece for musical instruments including a tubular body having an inclined upper wall, said upper wall being formed 25 thicker than that portion of the wall of the body opposite to the same, the inner surface of the inclined upper wall being hollowed out, as and for the purpose specified.

2. A mouth piece for musical instruments 30 comprising a body provided with a recess, the upper and lower walls of the recess being undercut, and a flexible shock absorbing pad fitted in said recess having its upper and lower ends bevelled and fitted under said 35 undercut walls, the pad being held in place by its inherent resiliency.

DUNCAN R. CLARK.
